UNITED STATES PATENT OFFICE.

OSCAR McDONALD, OF JERSEY CITY, NEW JERSEY.

DESIGN FOR A TOY.

SPECIFICATION forming part of Design No. 26,528, dated January 12, 1897.

Application filed December 7, 1896. Serial No. 614,849. Term of patent 3½ years.

To all whom it may concern:

Be it known that I, OSCAR McDONALD, of Jersey City, in the county of Hudson and State of New Jersey, have invented and produced a new and original Design for a Toy, of which the following is a full, clear, and exact description.

Reference is to be had to the accompanying drawings, forming a part of this specification, in which similar characters of reference indicate corresponding parts in both the figures.

Figure 1 is a front view of a toy embodying my new design, and Fig. 2 is a side view.

The design in its entirety consists of an elongated body *a*, having a loop *b* extending forwardly from the front end of the body, the round enlargement or whistle-head *c* at the junction of the loop and body, and the rotary blade *d*, supported in and ranging across the loop, the blade being **S** shape, as seen in edge

view, Fig. 2, and tapering in four directions, or diamond shape, as seen in plan. Further, the body has a bulbous formation *e* at its back end.

The leading feature of the design consists in the elongated body having a loop extending forwardly from the body, the loop having the blade therein of **S** shape, as seen in edge view.

Another feature is the enlargement or whistle-head at the junction of the elongated body and loop.

I claim—

The design for a toy herein shown and described.

OSCAR McDONALD.
